UNITED STATES PATENT OFFICE.

ANDRÉAS LODEWÝK KROM, OF UTRECHT, HOLLAND.

KEY-BOARD FOR MUSICAL INSTRUMENTS.

SPECIFICATION forming part of Letters Patent No. 367,148, dated July 26, 1887.

Application filed May 6, 1887. Serial No. 237,299. (No model.) Patented in Germany July 15, 1886, No. 40,046; in England March 8, 1887, No. 3,481, and in Belgium March 10, 1887, No. 76,642.

To all whom it may concern:

Be it known that I, ANDRÉAS LODEWÝK KROM, manufacturer, subject of the King of Holland, residing at Utrecht, No. 124 Schoutenstraat, Holland, have invented certain new and useful Improvements in or applicable to Piano-Fortes and Like Instruments, (for which Letters Patent have been granted in Germany, No. 40,046, dated July 15, 1886; Belgium, No. 76,642, dated March 10, 1887, and Great Britain, No. 3,481, dated March 8, 1887;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Referring to the drawings, Figure 1 is an end elevation of so much of an upright piano as is necessary to illustrate my invention. Fig. 2 is a vertical section of Fig. 1; and Fig. 3 is a section taken on or about on line $x-x$ of Fig. 2, showing the key-board reversed with the bank of keys b in their operative position.

The difficulties encountered by teachers in teaching the younger pupils to play on the piano or other similar key-instrument are well understood. These difficulties arise, chiefly, from the limited stretch of the pupil's fingers—the stretch of an octave, for instance, on the ordinary key-board being too great for a child. The means heretofore proposed to remedy this difficulty, by supplying interchangeable key-boards the bank of keys which vary in range, are very complicated and costly and require skill and experience in effecting the changes.

The object of my invention is to remedy this difficulty; and it consists in a reversible key-board having two banks of keys varying in range and interchangeable relatively to the action or mechanism that operates the sound-producing devices, as hereinafter fully described, and as set forth in the claims.

In the drawings, d indicates a portion of the ends and the cheeks of the framing of an upright piano, in which cheeks is formed a groove, d' , and A indicates the key-board provided at its ends with pivots i , that have their bearings in the end boards of a sliding frame,

c. Each end board of the frame c is provided with a tongue, e , that fits into the groove d' in the cheeks of the piano-frame, so that said frame c can be drawn out and pushed back into the main frame and so that the said key-board A, when the frame is fully drawn out, can be reversed by rotating the same on its pivots i .

Upon one face of the key-board A is arranged the usual bank of keys, a , and upon the other face a bank of keys, b , of a less extent of range, but containing the same number of octaves, the keys b being made much narrower than the keys a to reduce the distance between the extreme keys of an octave or that between any two keys, so as to correspondingly reduce the stretch of the fingers. To obtain this result, the keys b are necessarily made to diverge from the center of the key-board to the opposite ends thereof, as shown in Fig. 3, in order to bring the inner end of the keys under their respective actions, the banks of keys a and b being reversely mounted on the key-board, so as to bring the operative ends of the keys in proper position after the key-board A has been swung around to bring the bank of keys b in the place of the bank of keys a , Fig. 2, for instance, or vice versa.

The pivoted key-board frame A, Fig. 1, is shown as fully drawn out and partly swung around on its pivots to bring the bank of keys b into the place of the bank of keys a .

If desired, the sliding frame c may be dispensed with, and the key-board A may be made to slide in and out of the piano-frame, in which case the pivots i of the key-board will have their bearings and slide in the grooves d' in the piano-frame; or the key-board A may be arranged to be completely withdrawn from the piano-frame and reversed bodily, in which case said key-board may be provided with a tongue that fits and slides in the groove d' in the ends or cheeks of the frame.

Of course a plurality of key-boards, each having one bank of keys only, and constructed to be interchangeably applied to the instrument, may be employed.

Having now described my invention, what I claim, and desire to secure by Letters Patent, is—

1. In musical instruments provided with a

key-board and keys, the combination, with the action or mechanism that operates the sound-producing devices, of a reversible key-board, as described.

5 2. In musical instruments provided with a key-board and keys, the combination, with the action or mechanism that operates the sound-producing devices, of a reversible key-board provided with two banks of keys varying in range, arranged on the opposite faces of said board, substantially as and for the purpose specified.

3. In musical instruments provided with a key-board and keys, the combination, with the action or mechanism that operates the sound-producing devices, of a reversible key-board provided with two banks of keys varying in range, but having the same number of octaves, arranged on opposite faces of said board, substantially as and for the purpose specified.

4. In a musical instrument provided with a key-board and keys, the combination, with the

action or mechanism that operates the sound-producing devices, of a pivoted key-board provided with a bank of keys on its opposite faces, adapted to be moved into and out of the frame of the instrument and rotate on its pivot when moved out, substantially as and for the purpose specified.

5. In a musical instrument provided with a key-board and keys, the combination, with the frame of the instrument and the action or mechanism that operates the sound-producing devices, of the sliding frame *c* and the key-board *A*, pivoted in said frame, said key-board being provided with two banks of keys, *a* and *b*, one on each of its faces, substantially as and for the purpose specified.

In testimony whereof I affix my signature in presence of two witnesses.

ANDRÉAS LODEWÝK KROM.
